UNITED STATES PATENT OFFICE.

JOHN A. MILLER AND JAMES H. WARMOTH, OF AUSTIN, TEXAS.

HARNESS-SADDLE.

SPECIFICATION forming part of Letters Patent No. 529,287, dated November 13, 1894.

Application filed July 30, 1894. Serial No. 519,031. (No model.)

To all whom it may concern:

Be it known that we, JOHN A. MILLER and JAMES H. WARMOTH, citizens of the United States, residing at Austin, in the county of Travis and State of Texas, have invented certain new and useful Improvements in Harness-Saddles; and we do hereby declare the following to be a full, clear, and exact description of the invention, such as will enable others skilled in the art to which it appertains to make and use the same.

Our invention relates to improvements in harness saddles, and it consists of certain novel features hereinafter described and claimed.

Reference is had to the accompanying drawings, in which the same parts are indicated by the same letters.

Figure 1 represents a perspective view of the adjustable frame used in our improved harness saddle. Fig. 2 represents a side elevation of the saddle. Fig. 3 represents a section along the line $x-x$ of Fig. 2 and looking to the right. Fig. 4 represents an enlarged detail view of the bearer loop, and the method of connecting the same to the saddle, and Fig. 5 represents a perspective view of the bearer loop.

A represents the saddle proper, which is provided with the check rein hook A', and the loop a' for the crupper-strap.

B represents a bent metal plate provided with a plurality of rivet holes near the end thereof, and covered with leather pieces C and D. The upper portion of this bent plate B is perforated to receive the screw bolt a, which passes through the saddle A, and into the lower end of the check-rein hook A' as shown in Fig. 3. The lower end of this hook is covered with leather E. The plates F also provided with a plurality of rivet-holes, are secured to the lower ends of this curved plate B. It will be seen that the lap of the plates over the plate B, may be varied by altering the relative positions of the rivet holes with each other, and then fastening the two plates together by the rivets f'. Screws or tap rivets may be used if desired.

The upper end of the plate F is provided with a screw-threaded hole f to receive the screw-threaded end of the terret R, should it be desired to move the terret up toward the

top of the saddle, while the lower end of each of the plates F is bifurcated as at f² to receive the pivoted end h' of the pad plate H. 55 This pad plate is provided with a hole h for the shank of the terret to pass through, and terminates at its lower end in a circular flange h² having a cylindrical lug h³ in the center thereof, which lug is perforated as at h⁰. 60

In order to make a neat joint, the lower end of the pad plate H is provided with a curved shoulder h⁴ as shown in Fig. 1.

The loop K for supporting the bearing straps L is provided with a circular hole k⁰ to 65 fits snugly over the cylinder h³, and terminates in a loop k' adapted to receive the strap L.

The bolt M having a screwthreaded end m, flanged top m', and spherical head m² perforated transversely as at m⁰ is passed down 70 through the hole h⁰ and the screwthreaded end engages in the female screwthread p of the nut P, which nut is flanged as at p' and is secured by means of the screws p² to the leather S.

It will be seen by an inspection of Fig. 4, 75 that the loop K will be securely though revolvably mounted on the pad plate H.

The pads T² are held between the stout strap T and the lining T', and are only connected to the saddle by means of the straps t, one on 80 either side. These straps t are free to slide up and down on the loose end of the strap S, and thus a ready adjustment of the pad to the back of the horse, may be readily obtained.

It will be noted that not only is the pad adjustable in a vertical direction, but that the pad plates are free to swing on their pivots h' and thus the saddle automatically adapts itself to the configuration of the back of the animal. 90

The terrets R are secured in position in a similar way to the bolt M, the screw-threaded end r of the shank of the terret engaging in a nut P similar to that already described.

Having thus described our invention, what 95 we claim, and desire to secure by Letters Patent of the United States, is—

1. In a harness saddle, the combination with a metallic frame hinged as shown, of straps S depending from said hinged portions, and pads T² connected together by a strap T, and the guide straps t secured to said pads and adapted to slide along said straps S, substantially as and for the purposes described. 100

2. In a harness saddle, the combination with a metallic frame composed of the curved plate B, the plates F connected thereto, the plates H pivotally connected to said plates F, and
5 provided with the flat circular ends h^2 , with the perforated cylindrical lugs h^3 , the supporter loops K having cylindrical apertures h^0 adapted to slip over said cylindrical lugs h^3 , bolts passing through said perforated lugs
10 and holding said supporter loops and said plates H together, the straps S depending from said hinged portions, the pads T ^{2} , the strap T

connecting said pads, and the guide straps t secured to said pads and adapted to slide along said straps S, substantially as and for 15 the purposes described.

In testimony whereof we affix our signatures in presence of two witnesses.

JOHN A. MILLER.

JAMES H. WARMOTH.
